US00D926810S

(12) **United States Design Patent** (10) Patent No.: **US D926,810 S**
Murphy et al. (45) Date of Patent: **** Aug. 3, 2021**

(54) **DISPLAY SCREEN OR PORTION THEREOF WITH A GRAPHICAL USER INTERFACE**

(71) Applicant: **REliaQUEST HOLDINGS, LLC**,
Tampa, FL (US)

(72) Inventors: **Brian P. Murphy**, Tampa, FL (US);
Joe Partlow, Tampa, FL (US); **Colin O'Connor**, Tampa, FL (US); **Jason Pfeiffer**, Tampa, FL (US)

(73) Assignee: **ReliaQuest Holdings, LLC**, Tampa, FL (US)

(**) Term: **15 Years**

(21) Appl. No.: **29/693,796**

(22) Filed: **Jun. 5, 2019**

(51) LOC (13) Cl. **14-04**

(52) U.S. Cl. **USPC D14/488**

(58) **Field of Classification Search**

(57) **CLAIM**

The ornamental design for a display screen or portion thereof with a graphical user interface, as shown and described.

DESCRIPTION

The FIGURE is a front view of a display screen or portion thereof with a graphical user interface showing the claimed design.

The broken lines are included for the purpose of illustrating portions of the display screen or portion thereof with a graphical user interface that form no part of the claimed design.

1 Claim, 1 Drawing Sheet
